UNITED STATES PATENT OFFICE.

WILLIAM H. NUTT, OF NEWBURYPORT, MASSACHUSETTS.

DESIGN FOR A SHOE HEEL.

Application filed April 28, 1923. Serial No. 5,996. Term of patent 7 years.

To all whom it may concern:

Be it known that I, WILLIAM H. NUTT, a citizen of the United States, residing at Newburyport, in the county of Essex and Commonwealth of Massachusetts, have invented a new, original and ornamental Design for Shoe Heels, of which the following is a specification, reference being had to the accompanying drawings, forming a part thereof.

In the drawings:

Fig. 1 is a side elevation of a heel embodying my new design.

Fig. 2 is a rear elevation.

Fig. 3 is a bottom plan view.

Fig. 4 is a section on line 4—4, Fig. 1.

Fig. 5 is a section on line 5—5, Fig. 2.

Referring to Fig. 4 it will be noted that the vertical upwardly and downwardly tapering recesses are flat at their bottoms, thus affording considerable surfaces which, when the heel is finished, may be stained or painted in a different color than that in which the main part of the heel is finished, thereby increasing the pleasing ornamental effect.

What I claim is—

The ornamental design for a shoe heel, as shown.

WILLIAM H. NUTT.
